CLAIM

The ornamental design for a pocket scale, as shown and described.

DESCRIPTION

FIG. 1 is a front perspective view of a first embodiment of a pocket scale, showing my new design;

FIG. 2 is a top plan view of the embodiment of FIG. 1;

FIG. 3 is a bottom plan view of the embodiment of FIG. 1;

FIG. 4 is a left side elevational view of the embodiment of FIG. 1;

FIG. 5 is a right side elevational view of the embodiment of FIG. 1;

FIG. 6 is a front elevational view of the embodiment of FIG. 1;

FIG. 7 is rear elevational view of the embodiment of FIG. 1;

FIG. 8 is a front perspective view of a second embodiment of a pocket scale, showing my new design;

FIG. 9 is a top plan view of the embodiment of FIG. 8;

FIG. 10 is a bottom plan view of the embodiment of FIG. 8;

FIG. 11 is a left side elevational view of the embodiment of FIG. 8;

FIG. 12 is a right side elevational view of the embodiment of FIG. 8;

FIG. 13 is a front elevational view of the embodiment of FIG. 8; and,

FIG. 14 is a rear elevational view of the embodiment of FIG. 8.
